DROP TUBE FOR ICE CAN AGITATION

John C. Koch, Stockton, and Harry T. Holbrook,
Oakland, Calif.

Application October 9, 1936, Serial No. 104,804

4 Claims. (Cl. 62—159)

This invention relates generally to the ice making industry and in particular relates to an improved form of drop tube.

In the commercial production of ice it is common practice to inject air into the water being frozen in a can, the injection of air agitating the water and creating a concentration of impurities and salts toward the center of the can as the water freezes from the walls of the can inwardly. These impurities and salts finally become concentrated in an unfrozen core in the cake of ice and are removed by means of a "core pump." The core is then filled with clear water and the freezing of the block of ice completed. The injection of the air into the cans of water has heretofore been accomplished by means of fixed drop tubes depending into the water through which air is injected into the water at a fixed point. However, due to the fact that the point of injection was fixed, the water in the can remote from such point was not adequately agitated and some of the impurities and salts remained in the water as it froze. As a result, the clarity of the ice was impaired. It is therefore the principal object of our invention to provide a drop tube which, when in use and suspended in a can of water to be frozen, will automatically travel about in the can thereby assuring a recurring agitation of the water at all points in the can and a concentration of substantially all impurities and salts.

A further object of our invention is to provide an improved drop tube which is simple and inexpensive and yet effective for the purpose for which it is designed.

Another object of our invention is to provide a unique method of concentrating the impurities and salt from the water, employing agitation created by air.

These objects we accomplish by means of such structure and relative arrangement of parts as will fully appear by a perusal of the following specification and claims.

In the drawing similar characters of reference indicate corresponding parts in the several views:

Figure 1 is an elevation of our improved drop tube, the float being shown in section.

Figure 2 is a perspective view of our improved drop tube as positioned for use in a can of water, one corner of the can being broken away.

Referring now more particularly to the characters of reference on the drawing, our improved drop tube comprises a relatively long slender tube 1. The upper end of this tube 1 projects centrally through a hollow, cylindrical float 2 and is se-

cured thereto in watertight connection. Although this float is preferably made of metal in cylindrical form, it may be possible to employ a rubber ball in place of the metal float.

The upper end of the tube projects a short distance beyond the top of the float into a ferrule 3 which is secured to such projecting end as well as to the top of the float. A tapered air supply connection is removably engaged in the open end of the ferrule 3. A flexible rubber hose 5 is connected at one end to connection 4 and at the other end to an air supply pipe 6 extending transversely of a water retaining can 7 in which the drop tube is disposed in the manner shown in Fig. 2.

The tube 1 is provided with a series of small holes 8 in its length as well as a pair of spaced holes 9 within the float 2.

Operation

Our improved drop tube is employed in the following manner:

The can 7, which is surrounded by the brine, is filled with water to a level some distance below the top. The drop tube is then placed in the water; the tube being of such length that when suspended from the float, the lower end of the tube will be several inches from the bottom of the can. The tapered connection 4 is placed into ferrule 3 in order that air may be supplied to the tube 1.

As the air discharges from the lower end of tube 1, the air bubbles agitate the water surrounding the tube and float. When this occurs, the float is unstabilized and the tube will swing in one direction or the other from its initial vertical position as shown in Fig. 2. This results in the tube discharging the air into the water in such direction as to cause the discharging air to propel the tube and float about the tank. The flexibility of rubber hose 5 as well as its length permits the tube and float to travel about freely and without material restriction.

As the tube and float are thus propelled about the can, the water in the tank is agitated at every point and the impurities and salts effectively concentrated out of all of the water into the center core area.

Of course, as the water begins to freeze inwardly from the edges of the can, the path of travel of the continually moving tube will be gradually restricted and finally the tube will be frozen into the cake of ice after the core is pumped out and refilled. After being frozen into the cake of ice, hot water is injected into the tube, the hot water passing through holes 8 to free the tube and

through holes 9 into the float to free it from the ice.

From the foregoing description it will be readily seen that we have produced such a device as substantially fulfills the objects of the invention as set forth herein.

While this specification sets forth in detail the present and preferred construction of the device, still in practice such deviations from such detail 10 may be resorted to as do not form a departure from the spirit of the invention, as defined by the appended claims.

Having thus described our invention, what we claim as new and useful and desire to secure by 15 Letters Patent is:

1. In ice making apparatus, an open top ice making can adapted to contain a quantity of water, an air supply pipe disposed above the open top of the can, a float adapted to be supported by the water in the can, a relatively long tube open at its lower end secured to the float and depending therefrom into the water, and a flexible hose connected at one end to the air supply pipe and at the other end to the upper 20 end of the tube; said flexible hose being of sufficient length so that the float may travel to any point in the can in an undetermined course and without material restriction.

2. In ice making apparatus, an open top ice making can of relatively great length, adapted to contain a quantity of water, an air supply connection disposed above the open top of the can at a point substantially central between the

ends of the can, a float adapted to rest on the surface of the water, a relatively long tube open at its lower end secured to the float and depending therefrom into the water, and a flexible hose connected at one end to the air supply connection and at the other end to the upper end of the tube; said flexible hose being of a length substantially equal to one half the length of the can so that the float and attached tube may travel from one end of the can to the other in an undetermined course and without material restriction. 10

3. A drop tube unit for use in connection with ice making, comprising a relatively long tube open at its lower end, a float secured to said tube 15 adjacent its upper end, and flexible air supply means secured in connection with said tube; the float being hollow and the tube having holes communicating with the interior of the float.

4. In ice making apparatus, an open top ice 20 making can adapted to contain a quantity of water, a float adapted to be supported by the water in the can, a relatively long tube open at its lower end secured to the float and depending therefrom into the water, and flexible air 25 supply means secured in connection with said tube at its upper end; said means being arranged so that the float may travel to any point in the can in an undetermined course and without material restriction.
